UNITED STATES PATENT OFFICE.

MARIA C. SCHERER, OF BAYONNE, NEW JERSEY.

DESIGN FOR A CHATELAINE.

SPECIFICATION forming part of Design No. 22,107, dated January 10, 1893.

Application filed December 15, 1892. Serial No. 455,310. Term of patent 3½ years.

To all whom it may concern:

Be it known that I, MARIA C. SCHERER, a citizen of the United States, residing at Bayonne, Hudson county, New Jersey, have invented and produced a new and original Design for a Chatelaine, of which the following is a specification, reference being had to the accompanying drawing, which represents a face view of my newly-designed chatelaine.

10 The leading feature of my design consists of a shield upon which is mounted a female figure above a building and a coin and from which several pendants are suspended.

a, represents a shield upon which is represented a female figure b, above a building c, 15 a coin d, and flags e. From the shield a, there are suspended a buffalo's head f, a pig g, scissors h, and a sausage i.

What I claim is:

The design for a chatelaine substantially 20 as herein shown and described.

MARIA C. SCHERER.
